UNITED STATES PATENT OFFICE.

FREDERICK W. FELLOWS, OF LOS ANGELES, CALIFORNIA.

MUSICAL INSTRUMENT.

Application filed April 19, 1923. Serial No. 633,109.

The principal object of my invention is to provide an improved keyboard and associated mechanism by means of which one player can control a sufficiently large number 5 of tone-producing elements of fixed pitch to enable him to play chords and intervals in just, or perfect, intonation, or in any desired degree of approximation thereto, thus correcting the imperfect chords and intervals of 10 equal temperament by substituting therefor chords and intervals of the maximum degree of consonance, or of any desired degree of approximation thereto.

I accomplish the desired result by providing a key-board, preferably of symmetrical form and arrangement, with a large number 15 of tone-producing elements, with connections whereby each key can be made to control a plurality of different pitches, and 20 with a selective control mechanism by means of which different groups of said tone-producing elements can be selectively connected to said key-board at will.

In order to explain my invention in detail, I have illustrated one embodiment thereof 25 on the accompanying sheets of drawings, which I will now describe.

Figure 1 shows a side elevation of a key-board embodying my invention;

Figure 2 shows a top plan view thereof, 30 with parts broken away;

Figure 3 shows an enlarged rear end view of a key-lever;

Figure 4 is a front perspective view of a 35 part of a key-board;

Figure 5 is a schematic view showing groups of keys separated from each other in order to show the electrical connections from the keys, to the tone-producing elements, and 40 to the selective control mechanism;

Figure 6 shows one form of mechanism for actuating the selective control mechanism; and

Figures 7 to 15, inclusive, shows top plan 45 views of the digital or finger portions of the keys of a key-board, representing, respectively, nine different settings made possible by the control mechanism.

Referring now more in detail to the drawings, I will first describe the keys or levers 50 making up the key-board proper. There are two forms of key-levers used. 1 designates one form of key-lever, of which there are

three shown in Fig. 1, making up one vertical tier of keys, set one above the other, and each positioned rearwardly a distance substantially equal to the length of the digital, or finger, portion of the key, as shown. 2 designates the other form of key-lever, of which there are also three shown in Fig. 1, 55 with their digital portions shown to be substantially a third higher than the digital portions of the keys 1, and these key-levers 2 are also set rearwardly to overlap longitudinally about half of the digital portions of two of the keys 1, as may be seen in Figs. 1, 2, and 4. It will be noted that the key-board is symmetrical in form and arrangement, and that each vertical tier of keys is of uniform horizontal breadth, and that each bank of keys 60 forms a straight line across the key-board.

Each horizontal row of key-levers is pivotally mounted on a bearing bar, as 3, supported at its opposite ends in the frame work of the instrument in any suitable manner, 70 the bearing or pivotal bars being so positioned relative to the length of the key-lever that the digital part of the key, or that part which is engaged by the finger of the player is the lighter, the longer end being the 75 heavier and normally returning the key to its original position after the key end has been depressed and then released. A limit bar or stop, 4, is shown under the forward ends of each horizontal row of keys, and each key is 80 provided in its under side with a pin socket 85 to receive a pin, as at 5, which pin projects upwardly from the limit bar, and prevents any lateral or longitudinal movement of the key as it is depressed.

The rear end of each key-lever is reduced in thickness, as at 1^a, and 2^a, Fig. 2, to provide room for electric contact members, herein-after again referred to. The rear ends of the different rows of key-levers are positioned over a step-like structure, 6, 6, 6, and each key lever is held and guided at its rear end by means of a pin, 7, set in said step-like structure. As the forward, or digital, end of the key-lever is depressed, the rear end of the lever is moved upwardly from the step-like structure, 6, as will be clear. The entire key-board is made up of alternate vertical groups of keys, 1 and 2, as will be clear from Figs. 1, 2 and 4.

The purpose of the keys is to make and

break the electrical circuits which control the speaking of the reeds, pipes, or other tone-producing elements of the instrument. The present embodiment of the invention shows 5 and describes an electrical control mechanism.

Each key controls, one at a time, more than one pitch, and is, therefore, provided with as many sets of making and breaking devices 10 as there are pitches under its control. Adjacent to the rear end of each key-lever, are pairs of contact members, as 8, 8, the upper or free ends of each pair being slightly bent and bearing against the reduced part of the 15 end of the key, as seen in Fig. 3. Mounted on the lower part of the reduced portion of the key, is a metal contact plate as 9, adapted, when the front end of the key is depressed, to be raised until it contacts with and connects said ends, and thus completes a circuit through said contact elements, 8, 8. The 20 number of pitches controlled, one at a time, by a given key-lever, depends upon its relative position upon the key-board, and the 25 principles by which this number is determined will be explained hereafter.

For convenience of reference, the rows of keys in Fig. 2 are numbered consecutively from .1 to .37 along the front ends of the 30 digital portions of the keys. The digital portions of the keys are also numbered thereon with Roman numerals in the following manner. The six keys at the upper side of the sheet, or the left-hand side of the key-board, 35 in the front row, are numbered from I to VI, inclusive. The next six keys in the front row are also numbered from I to VI, and the next six keys are so numbered. The second row of keys, or the second bank, are also numbered in groups of six, but number I starts between 40 digits IV and V of the front row. The third and fourth rows, or banks of keys are also so numbered, number I starting between 45 numbers IV and V of the row immediately in front of it. In this way, the entire key-board is symmetrically divided into groups of six digits each, the significance of which will appear later. Thus any digital can be referred to specifically by mentioning its order 50 number and its Roman numeral, thus, Digital .22—I is that digital bearing the Roman numeral I, lying in the twenty second vertical row from the top of the sheet, or the left hand side of the key-board.

55 It is assumed that no key-board playable manually is possible where there is a separate key for each pitch. In the present invention, advantage is taken of the fact that in a given musical composition tones which are closely related to the key note are more apt to be used than those more remotely related. It is, therefore, arranged so that the scale of the key of the composition, together with scales related to it by perfect fifths, are temporarily 60 connected with the key-board, while scales

more remotely related are at the same time disconnected. It results, as a consequence, that the several tones of the instrument are controlled not alone by the different digitals, but also by different "settings" of the tones 70 upon the keyboard. Thus each digital does duty for several pitches, one at a time, and also, in its various relations to the several scales in which it occurs, a given pitch may be controlled by more than one digital. 75

The settings are not limited in number or kind, but nine are shown as being most useful. Settings 1 to 9, inclusive, are shown in Figs. 7 to 15, inclusive. The nine different settings are represented on the nine different 80 representations of the key-board.

A pitch suitable for middle C is chosen from which all other tones of the instrument are calculated. Middle C is, therefore, designated by the vibration ratio $\frac{1}{1}$, and the 85 pitch of every other tone is calculated with reference to the pitch of this tone and is represented by a fraction, or vibration ratio, the denominator of which corresponds to the number of vibrations executed by middle C, 90 in the same interval of time that the tone represented by the fraction executes the number of vibrations indicated by its numerator. Where the numerator is less than the denominator, the tone is lower in pitch than middle C. Where the numerator is greater than the denominator, the tone is higher in pitch than middle C. 95

In every setting, all digitals positioned relative to each other as are .1—I, .13—I, .25—I, 100 and .37—I, form an ascending series of octaves, in the order named, and all digitals positioned relative to each other as are .1—I, .8—I, .15—I, .22—I, .29—I, and .36—I, form an ascending series of perfect fifths, in the 105 order named. The key-board is, therefore, symmetrically arranged and the fingering of all similar scales is similar. This greatly simplifies execution.

In a given setting, not all digitals can be 110 used for key-notes. The digitals which can be used for key-notes in the several settings are as follows:

In setting No. 1, Fig. 7, all digitals bearing Roman numeral III. In settings 2 and 3, 115 Figs. 8 and 9, all digitals bearing Roman numeral V. In settings 4 and 5, Figs. 10 and 11, all digitals bearing Roman numeral I. In settings 6 and 7, Figs. 12 and 13, all digitals bearing Roman numeral III. In settings 8 and 9, Figs. 14 and 15, all digitals bearing Roman numeral V. It will be noticed that in a given setting the keynotes are a perfect fifth apart, repeated by octaves higher and lower throughout the compass of the key-board. Thus modulation upward or downward by perfect fifths is provided for without change of setting. 125

Settings 1, 3, 5, 7 and 9 are of one type, in that each gives the same series of intervals 130

between tones, but at different pitches, while settings 2, 4, 6 and 8, are of another type, giving another series of intervals between tones, but at different pitches. These two types alternate with each other so that they may be switched upon the keyboard by the selective control mechanism, in the order 1, 2, 3, 4, 5, 6, 7, 8 and 9, and one may stop at any setting and retrace one or more of the series of settings at will.

In the first, or odd-numbered type of setting, every digital bearing a key-note, together with the five digits immediately to its right, at the same level, forms with the 15 said keynote the following intervals: $\frac{1}{4}, \frac{3}{8}, \frac{5}{4}$, $\frac{17}{12}, \frac{19}{12}, \frac{7}{4}$ in the order named, as, for instance, digits .22—I, .24—II, .26—III, .28—IV, .30—V, and .32—VI in setting No. 5 bear these identical intervals, and no further calculation is necessary to establish the proposition as to them. In other groups, calculation shows the same intervals between the respective tones, as, for instance, in the same setting, on digits .27—I, .29—II, .31—III, .33—IV, .35—V, and .37—VI occur the 25 pitches $\frac{4}{3}, \frac{3}{2}, \frac{5}{3}, \frac{17}{9}, \frac{19}{9}$, and $\frac{7}{3}$, respectively. By multiplying each of these fractions by $\frac{3}{2}$ (the pitch of the keynote inverted) and reducing each resulting fraction to its lowest terms, we obtain the fractions $\frac{1}{4}, \frac{3}{8}, \frac{5}{4}, \frac{17}{12}, \frac{19}{12}$, and $\frac{7}{4}$, respectively, as above. The reason for multiplying each fraction by the pitch of the keynote inverted is that we thus transpose the keynote to the pitch of middle C, or $\frac{1}{4}$, and at the same time we equally transpose each of the other tones of the group so as to maintain their pitches relative to each other.

In setting No. 3, every tone of setting No. 1 is transposed upward a major third and positioned upon the second digital to the right of, and occurring at the same level as, that upon which it is found in setting No. 1. Setting No. 5 is a similar transposition of the tones of setting No. 3; and setting No. 7 and No. 9 45 are similar transpositions of the tones of settings 5 and 7, respectively. That is, by changing from one odd numbered setting to the next numerically higher setting of the same series, we transpose the tones of the entire key-board upward a major third and position them upon keys four semi-tones to the right. Thus, the keynotes pass in order, to the right, through the following series of digits: III—V—I—III—V. While the keynotes are found upon digits III in both setting No. 1 and setting No. 7, the absolute pitch of the respective tones positioned upon the same digits varies by the interval $\frac{17}{8}$, or the defect of three major thirds from an 50 octave known as a great diesis. This is also true of settings 2 and 9, in both of which the keynotes are found upon digits numbered V, but the absolute pitch of the tones controlled by the same digital varies by the same 55 interval.

By taking twelve keys of any of the odd numbered settings positioned relatively to any keynote as are digits .23—IV, .24—II, .25—V, .26—III, .27—I, .28—IV, .29—II, .30—V, .31—III, .32—VI, .33—III and 70 .34—I, to digital .22—I, in setting No. 5, we obtain a chromatic scale of the following intervals: $\frac{1}{4}, \frac{17}{12}, \frac{3}{8}, \frac{19}{12}, \frac{5}{4}, \frac{4}{3}, \frac{17}{12}, \frac{19}{12}, \frac{7}{4}, \frac{15}{8}, \frac{2}{3}$.

This chromatic scale contains the tones of maximum consonance to be used in making 75 chords with the major third formed by its first and fifth tones, (or $\frac{1}{4}$ and $\frac{5}{4}$). The tones $\frac{1}{4}, \frac{3}{8}, \frac{5}{4}, \frac{4}{3}, \frac{2}{3}, \frac{5}{3}, \frac{15}{8}$, and $\frac{7}{4}$, contained in said chromatic scale, form the major diatonic scale.

In the second, or even-numbered type of setting, every digital bearing a keynote, together with the five digits immediately to its right, at the same level, form with the said keynote the following intervals: $\frac{1}{4}, \frac{3}{8}, \frac{5}{4}, \frac{15}{8}, \frac{3}{5}, \frac{5}{3}$, in the order named, as for instance, digits .22—I, .24—II, .26—III, .28—IV, .30—V and .32—VI in setting No. 4 bear these identical intervals, and no further calculation is necessary to establish the proposition as to them. In other groups, calculation shows the same intervals between the respective tones, as, for instance, in the same setting, on digits .27—I, .29—II, .31—III, .33—IV, .35—V, and .37—VI occur the 90 pitches $\frac{4}{3}, \frac{3}{2}, \frac{5}{3}, \frac{15}{8}, \frac{3}{5}$ and $\frac{12}{5}$, respectively. By multiplying each of these fractions by $\frac{3}{2}$, for reasons heretofore explained in connection with the first type of setting, we obtain the fractions $\frac{1}{4}, \frac{3}{8}, \frac{5}{4}, \frac{15}{16}, \frac{5}{8}, \frac{5}{3}$, respectively, 100 as above.

As in the odd-numbered settings, setting No. 4 is a transposition of setting No. 2 upward a major third; setting No. 6 is a similar transposition of setting No. 4, and setting No. 8 is a similar transposition of setting No. 6.

The keynotes of setting No. 1 are identical with those of setting No. 2; those of setting No. 3, with those of setting No. 4; those of setting No. 5, with those of setting No. 6, and 110 those of setting No. 7 with those of setting No. 8.

By taking seven keys of any of the even-numbered settings, positioned relatively to any keynote as are digits .24—II, .26—III, .27—I, .29—II, .31—III, .33—IV, and .34—I to digital .22—I in setting No. 4, we obtain the major diatonic scale, consisting of the following intervals, in the order named:

$\frac{1}{4}, \frac{3}{8}, \frac{5}{4}, \frac{4}{3}, \frac{2}{3}, \frac{5}{3}, \frac{15}{8}$ and $\frac{7}{4}$.

Also by taking seven keys of any of the even-numbered settings, positioned relatively to any keynote as are digits .24—II, .25—VI, .27—I, .29—II, .30—V, .33—IV, and .34—I to digital .22—I in setting No. 4, 125 we obtain the minor diatonic scale in its harmonic form. Digital .32—VI indicates the relative position of the flat seventh used in the descending melodic form of this minor scale, and digital .31—III indicates the rela- 130

tive position of the sharp sixth used in the ascending melodic form of the minor scale.

Gathering into one table the several pitches controlled by digitals .22—I, .24—II, .26—III, .28—IV, .30—V, and .32—VI, we have the following, in which the Roman

numeral of the digital appears at the left of the horizontal row of pitches controlled by the digital in the several settings whose numbers appear, respectively, at the top of the table.

SETTINGS.

	9	8	7	6	5	4	3	2	1
I	$\frac{125}{128}$	$\frac{125}{128}$	$\frac{95}{96}$	$\frac{1}{1}$	$\frac{1}{1}$	$\frac{1}{1}$	$\frac{1}{1}$	$\frac{1}{1}$	$\frac{7}{8}$
II	$\frac{425}{384}$	$\frac{1125}{1024}$	$\frac{35}{32}$	$\frac{9}{8}$	$\frac{9}{8}$	$\frac{9}{8}$	$\frac{17}{15}$	$\frac{9}{8}$	$\frac{25}{24}$
III	$\frac{475}{384}$	$\frac{5}{4}$	$\frac{5}{4}$	$\frac{5}{4}$	$\frac{5}{4}$	$\frac{5}{4}$	$\frac{19}{15}$	$\frac{32}{25}$	$\frac{25}{24}$
IV	$\frac{175}{128}$	$\frac{45}{32}$	$\frac{45}{32}$	$\frac{45}{32}$	$\frac{17}{12}$	$\frac{45}{32}$	$\frac{7}{5}$	$\frac{35}{25}$	$\frac{25}{24}$
V	$\frac{25}{16}$	$\frac{25}{16}$	$\frac{25}{16}$	$\frac{25}{16}$	$\frac{19}{12}$	$\frac{8}{5}$	$\frac{8}{5}$	$\frac{8}{5}$	$\frac{8}{5}$
VI	$\frac{225}{128}$	$\frac{225}{128}$	$\frac{85}{48}$	$\frac{225}{128}$	$\frac{7}{4}$	$\frac{9}{5}$	$\frac{9}{5}$	$\frac{9}{5}$	$\frac{135}{128}$

Inasmuch as the arrangement of perfect fifths and octaves upon the key-board is symmetrical, any digital may be viewed as being a certain number of perfect fifths or octaves (or a combination of both) from one of the digitals mentioned in the last paragraph, and any similar group of six digitals bearing the Roman numbers I, II, III, IV, V, and VI, wherever located upon the keyboard, may be looked upon as controlling pitches which are a transposition of the pitches mentioned in the above table by that number of perfect fifths or octaves (or combination of both) which separates its digital bearing the Roman numeral I from digital .22—I. That is, we may determine the respective pitches controlled by any group of digitals similar to .22—I, .24—II, .26—III, .28—IV, .30—V, and .32—VI, and bearing the same Roman numerals in the same order, by multiplying the ratios of the table by the constant multiplier which is the fraction derived by multiplying together the vibration ratios of the number of perfect fifths or octaves, or combinations of both, by which digitals No. I are separated in the two groups. Thus, digital .27—I is removed from digital .22—I an octave up plus a perfect fifth down. The interval between the two digitals is, therefore, $\frac{4}{3} \times \frac{2}{3}$, or $\frac{4}{3}$, which is a perfect fourth up. By multiplying the fractions of line I of the table by $\frac{4}{3}$, all the pitches controlled by digital .27—I, as shown in the drawings illustrating setting No. 1 to No. 9, inclusive, will be derived.

In each setting, therefore, the entire key-board is divided into groups of six digitals each, similar to the group consisting of digi-

tals .22—I, .24—II, .26—III, .28—IV, .30—V, and .32—VI, and bearing the same Roman numerals in the same order. Each of these groups controls the same intervals, though at different pitch for each group. All digitals bearing the same Roman numeral are, therefore, controlled as a group. This is accomplished by means of a selective control mechanism which I will now describe, referring to Figs. 5 and 6.

Referring to the lower left hand side of Fig. 5, there is shown a diagram or face view of an electric selective control mechanism, the arrangement of which, it will be recognized, is similar to the arrangement of the table above given. This device really comprises a member, as 15, having a face or contact area divided into six divisions in one direction, as designated by the Roman numerals I to VI inclusive, and these divisions are again divided in the other direction into smaller divisions, nine being shown and representing nine different settings, as indicated. Mounted to move across said face or contact area is a connecting contact bar, 16, having six contact parts, as 16', or one for each of the six divisions designated by the Roman numerals I to VI. It will be noted that electric wires, represented by the broken lines running into said diagram, are connected, one to each division. It will also be seen that some of the contact divisions comprise an area equal to two, or four or even five of the smallest or unit divisions or sections. By comparing the table herein given with the contact face divisions, and the fractions therein written, it will be seen that they are the same. For example, the first two

fractions in settings 9 and 8 of the table are the same $\frac{12}{12}$, while the fractions in settings 6, 5, 4, 3 and 2, opposite Roman numeral I, of the table, are the same, namely, $\frac{1}{1}$, therefore, the first area on the contact face, or member 16, in the upper left hand corner, is equal to two of the unit areas, while the third area in the same line is equal to five of the smaller or unit areas. In other words, the 5 small areas or contact divisions of the electrical selective control mechanism contain the vibration ratios corresponding to the table, and from each area extends an electric circuit wire and these wires are connected to the 10 contact members 8, 8, at the rear ends of the key-levers, as hereinbefore described, and represented in Fig. 3, and thence they extend to the tone-producing elements, designated 17, Fig. 5, thence through a main line 15 18, to a battery, 19, and thence to the multiple contact bar or member 16, through the line 20. In Fig. 6, the member 15 is shown to be in curved form, with a wiper or multiple contactor 16^a carried on a ratchet wheel, 21, 25 adapted to be moved in either direction by means of pawls, 22 and 23, on opposite sides of the ratchet wheel 21, said pawls being carried on movable members, 24 and 25, respectively, capable of being moved manually at 30 will, as by means of knee pieces, 26 and 27. A spring detent holding element, as 28, is shown for yieldingly holding the ratchet wheel in different positions of adjustment, as will be clear from the showing made. I 35 do not limit my invention to any particular kind of means for operating the selective control mechanism, as many different mechanisms can be adopted to perform this service.

When the multiple contactor 16 is adjusted 40 to any one of its nine different positions, it is in contact with six of the contact faces or areas, one for each of the six Roman numerals appearing on the digital portions of the keys of the key-board. The keys are divided 45 into groups of six, and are numbered by the Roman numerals from I to VI, as before explained. The nine different positions of the multiple contact bar or member 16, changes the pitches of the keys numbered with the 50 Roman numerals according to the contact face or unit area. For example, in Fig. 5, the position of said contact bar 16, is at setting No. 4. If it should be moved to position of setting 3, only the pitches of keys bearing the Roman numerals II, III and IV 55 would be changed. If said contact bar were moved to the left to the position of setting 5 only the pitches of keys having the Roman numerals IV, V, and VI would be changed, 60 for only three contact areas are changed.

From each of the contact areas in line horizontally with the Roman numeral I, runs a line which branches to every key bearing the numeral I. This is also true of the contact 65 areas opposite the other Roman numerals up

to VI. Referring to the horizontal row of contact areas or faces opposite Roman numeral II, of member 15, of Fig. 5, it will be seen that the fourth and sixth contact faces have the same vibration ratio and therefore 70 control the same pitches. The circuit wires from these two contact faces are, therefore, joined, as at 30. A single wire cannot be used for the reason that another contact area is between them. This is also true in the areas opposite Roman numerals IV and VI, where the wires are joined at 31 and 32. Where several different circuits control the same pitch, the wires merge or join at any suitable position before reaching the tone-producing element, 80 as at 33, Fig. 5. It is assumed, of course, that the speaking of the pipes, or reeds, or other tone-producing elements, is controlled by any suitable electric, pneumatic, or other mechanism, of which there are many on the 85 market, and as this does not enter into the heart of the invention here presented, it is not necessary to go into further details about it. The tone-producing elements are sufficiently illustrated by the small circles, 17, 90 before referred to.

Assuming now that the contact bar or member 16 is in the position shown in Fig. 5 of the drawings, and that key .33—V be depressed. This key has three making and 95 breaking sets at its rear end and therefore controls three circuits and three pitches. When depressed, all three circuits are closed at its rear end, and if not broken elsewhere, pitches $\frac{256}{135}$, $\frac{152}{81}$, and $\frac{50}{27}$ would be sounded. By tracing the downward course of the three circuits from the rear of this key to the selective mechanism 15, it will be found that they terminate in contact areas in which are the ratios $\frac{8}{5}$, $\frac{12}{5}$, and $\frac{25}{16}$, respectively, and the contactor is in contact with area $\frac{8}{5}$ only. The other two circuits are broken at the selective mechanism and only tone producing element $\frac{256}{135}$ will sound. 100

Assuming that at the same time key .33—V 110 was depressed, we had depressed keys .28—V. These two keys are a perfect fourth apart upon the key-board, and two pitches obtained should be separated by that interval (vibration ratio $\frac{4}{3}$). Key .28—V controls pitches $\frac{64}{45}$, $\frac{32}{27}$, and $\frac{25}{18}$, and their circuits run, respectively, to areas $\frac{8}{5}$, $\frac{12}{5}$, and $\frac{25}{16}$ in the fifth horizontal row of contact areas of the selective control mechanism 15, but the contact member 16 is in contact with area $\frac{8}{5}$ only, the other circuits being broken at the control mechanism 15, and only pitch $\frac{64}{45}$ sounds. By multiplying the ratio $\frac{64}{45}$ by $\frac{4}{3}$ we obtain $\frac{256}{135}$ (the pitch obtained above by depressing key .33—V) proving that the two tones differ by 120 the interval of a perfect fourth, as required by the theory.

Referring to Fig. 11 (setting 5), it will be noted that the following digitals bear these respective vibration ratios, to-wit: 130

Digital number.	Vibration ratio.	Equivalent vibration ratios.
5 .34—VI	$\frac{63}{32}$	$\frac{21}{16} \frac{2}{3}$
.33—III	$\frac{15}{8}$	$\frac{20}{16} \frac{2}{3}$
.32—V	$\frac{57}{32}$	$\frac{19}{16} \frac{2}{3}$
10 .31—II	$\frac{27}{16}$	$\frac{18}{16} \frac{2}{3}$
.30—IV	$\frac{51}{32}$	$\frac{17}{16} \frac{2}{3}$
.29—I	$\frac{3}{2}$	$\frac{16}{16} \frac{2}{3}$
15 .28—III	$\frac{45}{32}$	$\frac{15}{16} \frac{2}{3}$
.27—VI	$\frac{21}{16}$	$\frac{14}{16} \frac{2}{3} \dots \frac{21}{16}$
.26—III	$\frac{5}{4}$	$\dots \frac{20}{16}$
20 .25—V	$\frac{19}{16}$	$\dots \frac{19}{16}$
.24—II	$\frac{9}{8}$	$\dots \frac{18}{16}$
.23—IV	$\frac{17}{16}$	$\dots \frac{17}{16}$
25 .22—I	$\frac{1}{1}$	$\dots \frac{16}{16}$
.20—VI	$\frac{7}{8}$	$\frac{21}{24} \dots \frac{14}{16}$
.19—III	$\frac{5}{6}$	$\frac{20}{24} \dots$
.18—V	$\frac{19}{24}$	$\frac{19}{24} \dots$
30 .17—II	$\frac{3}{4}$	$\frac{18}{24} \dots$
.16—IV	$\frac{17}{24}$	$\frac{17}{24} \dots$
.15—I	$\frac{2}{3}$	$\frac{16}{24} \dots$
35 .14—III	$\frac{5}{8}$	$\frac{15}{24} \dots$
.13—VI	$\frac{7}{12}$	$\frac{14}{24} \dots \frac{21}{36}$
.12—III	$\frac{5}{9}$	$\dots \frac{20}{36} \dots$
40 .11—V	$\frac{19}{36}$	$\dots \frac{19}{36} \dots$
.10—II	$\frac{1}{2}$	$\dots \frac{18}{36} \dots$
.9—IV	$\frac{17}{36}$	$\dots \frac{17}{36} \dots$
45 .8—I	$\frac{4}{9}$	$\dots \frac{16}{36} \dots$
.7—III	$\frac{5}{12}$	$\dots \frac{15}{36} \dots$
.6—VI	$\frac{7}{18}$	$\dots \frac{14}{36} \dots$

- 50 Here we have an ascending series of semitones, of varying width, according to the following plan: The vibration ratios of the eight lowest tones are to each other as the numbers 14, 15, 16, 17, 18, 19, 20, and 21, respectively; of the 8th to 15th tones, inclusive, as the same numbers; of the 15th to 22d tones, inclusive, as the same numbers; and of the 22d to 29th tones, inclusive, as the same numbers. All 55 tones seven semitones apart are separated by the interval of a perfect fifth. We have here, therefore, seven series of perfect fifths blended into one series of semitones, which may be extended upward and/or downward at will, 60 so positioned relatively to each other that the 65

intervals, $\frac{14}{15}$, $\frac{15}{16}$, $\frac{16}{17}$, $\frac{17}{18}$, $\frac{18}{19}$, $\frac{19}{20}$, and $\frac{20}{21}$, are continually repeated in the ascending order named at intervals of a perfect fifth. Inasmuch as all chromatic scales whose key-notes are a perfect fifth apart are founded on this series, applicant has, for the purposes of this application for patent, named this series of semitones the "chromatic series." In the remaining diagrams illustrating the odd numbered settings, this same chromatic series will be found transposed one or more major thirds, and in each of the odd numbered settings the remainder of the digitals will be found to bear only octaves of its tones. It will be noted in each instance that the chromatic series is positioned upon contiguous digitals in whatever octave it may occur. Applicant believes that he is the first to conceive and describe this chromatic series and/or to provide it with a keyboard. It is to be understood that this chromatic series, as well as the diatonic series and the double diatonic series hereinafter to be described may be extended upward and downward through any number of semitones to any desired pitch upon the principles described.

Referring to Fig. 10 (setting 4), it will be noted that the following digitals bear these respective vibration ratios, to-wit:

Digital number.	Vibration ratio.	Equivalent vibration ratios.
36—I	$\frac{9}{4}$	$\frac{16}{7} \frac{1}{9}$
35—IV	$\frac{135}{64}$	$\frac{15}{7} \frac{1}{9}$
33—III	$\frac{15}{8}$	$\dots \frac{20}{16} \frac{2}{3}$
31—II	$\frac{27}{16}$	$\dots \frac{18}{16} \frac{2}{3}$
29—I	$\frac{3}{2}$	$\dots \frac{16}{16} \frac{2}{3}$
28—IV	$\frac{45}{32}$	$\dots \frac{15}{16} \frac{2}{3}$
26—III	$\frac{5}{4}$	$\frac{20}{16} \dots$
24—II	$\frac{9}{8}$	$\frac{18}{16} \dots$
22—I	$\frac{1}{1}$	$\frac{16}{16} \dots$
21—IV	$\frac{15}{16}$	$\frac{15}{16} \dots$
19—III	$\frac{5}{6}$	$\dots \frac{20}{24} \dots$
17—II	$\frac{3}{4}$	$\dots \frac{18}{24} \dots$
15—I	$\frac{2}{3}$	$\dots \frac{16}{24} \dots$
14—IV	$\frac{45}{32}$	$\dots \frac{15}{24} \dots$
12—III	$\frac{5}{9}$	$\frac{20}{36} \dots$
10—II	$\frac{1}{2}$	$\frac{18}{36} \dots$
8—I	$\frac{4}{9}$	$\dots \frac{16}{36} \dots$
7—IV	$\frac{5}{12}$	$\dots \frac{15}{36} \dots$

Here we have an ascending series of whole

tones of varying width, with regularly interspersed semitones, according to the following plan: The vibration ratios of the 1st to the 4th tones, inclusive, are to each other as 5 the numbers 15, 16, 18, and 20, respectively; of the 5th to the 8th tones, inclusive, as the same numbers; of the 9th to the 12th tones, inclusive, as the same numbers; of the 13th to the 16th tones, inclusive, as the same 10 number, etc. all numbers being counted from the bottom of the table. Every fourth tone, counting from any tone in the table, forms with the latter tone a perfect fifth. We have, therefore, four series of perfect 15 fifths blended into one series of tones, unlimited in extent upward and downward, in which the intervals $\frac{1}{5}$, $\frac{1}{6}$, $\frac{2}{9}$, and $\frac{3}{8}$ are continually repeated in the ascending order named, at intervals of a perfect fifth. In 20asmuch as all diatonic scales whose key-notes are a perfect fifth apart are founded on this series, applicant has, for the purposes of this application for patent, named this series the "diatonic series." Applicant believes 25 that he is the first to describe this diatonic series and/or to provide it with a keyboard.

In the same figure, in digitals .9—V, .11—VI, .13—I, .15—II, .16—V, .18—VI, .20—I, .22—II, .23—V, .25—VI, .27—I, .29—II, .30—V, .32—VI, .34—I, .36—II and .37—V, will be found this same series transposed upward a diatonic semi-tone (ratio $\frac{16}{15}$), except where the digital upon 35 which a transposed tone would fall lies outside the limits of the keyboard as illustrated, as in the case of the transposition of vibration ratio $\frac{5}{12}$. It will be noted that the digitals upon which are distributed the 40 diatonic series just referred to, dovetail with those upon which are distributed the same series a diatonic semitone lower, and two such series a diatonic semitone apart form semitones which are positioned upon contiguous digitals. Two of the "diatonic series" a diatonic semitone apart, applicant has, for the purposes of this application for patent, named the "double diatonic series." In the remaining diagrams illustrating the 45 even numbered settings, this "double diatonic series" will be found transposed one or more major thirds, and in each of the even numbered settings the remainder of the digitals will be found to bear only octaves of its tones. 50 It will be noted that in each instance the tones of the double diatonic series are positioned upon contiguous digitals in whatever octave or transposition they occur. Applicant believes that he is the first to conceive 55 and describe this "double diatonic series" and/or to provide it with a keyboard.

While I have shown one combination of instrumentalities embodying my invention, I am aware that many changes can be made 60 therein without departing from the real spirit

of my invention, and I do not, therefore, limit my invention to the showing made for illustrative purposes except as I may be limited by the hereto appended claims.

I claim:

1. In a musical instrument, in combination, a series of tone producing elements, a key-board for controlling said elements, said key-board consisting of key-levers having digital surfaces of substantially the same shape and size, arranged in vertical tiers, side by side, the said digital surfaces in each vertical tier being one above the other and successively positioned rearwardly at regular intervals, whereby the digital surfaces of alternate keys from left to right are in horizontal alignment and lie in the same plane, the digital surfaces of each tier lying between two parallel planes, and operative connections from said key-levers to said tone-producing elements, said connections being such that different groups of the same number of key-levers control corresponding groups of tone-producing elements, the pitches of the respective tones produced by each of said groups of tone-producing elements being separated by the same series of intervals.

2. In a musical instrument, in combination, a series of tone producing elements, a key-board consisting of key-levers with their respective digital surfaces of substantially the same shape and size, arranged in vertical tiers, side by side, the digital surfaces in each vertical tier being successively positioned rearwardly between parallel planes coincident with the opposite sides of said digital surfaces, all of the digital portions of alternate keys from left to right being in alignment horizontally and lying in the same plane; operative connections from said key-levers to said tone producing elements, and a selective control mechanism for connecting said key-levers by groups, said connections being adapted to connect each of said key-lever groups to a plurality of groups of tone producing elements, one group thereof at a time, the respective pitches of the tones produced by each of the groups of tone producing elements simultaneously connected being separated by the same series of intervals.

3. In combination, a key-board having keys of the same shape and size arranged in groups of the same number of keys each, a relatively larger number of tone-producing elements, operative connections from said key-board to said tone-producing elements, said connections being such that each group of keys control a plurality of groups of tone-producing elements, one group at a time, the pitches of the respective tone-producing elements in each group simultaneously connected to said keyboard being separated from each other by the same series of intervals, and a selective control mechanism for connecting at will, simultaneously, said groups of keys.

- with desired groups of tone-producing elements.
4. In a musical instrument, a series of tone-producing elements, a key-board for controlling the same, electrical connections from said key-board to said tone-producing elements, the several keys of said key-board having each a plurality of circuit-completing contact elements for completing a plurality of different circuits at that place, one of said contact elements being provided for each enharmonic pitch controlled by a key, said tone-producing elements being connected electrically for group control, and a selective control mechanism adapted to be manipulated to control selectively the group of tone-producing elements connected with said key-board.
5. In a musical instrument, in combination, a series of tone-producing elements, a key-board for controlling the same, each key thereof controlling a plurality of enharmonic pitches, electrical connections from said tone-producing elements to said key-board, each key being adapted to control a plurality of circuits, the different circuits being connected to control different groups of tone-producing elements, and a selective control mechanism adapted to be manipulated to connect selectively a desired group of tone-producing elements with said key-board.
6. In a musical instrument, in combination, a series of tone-producing elements, a symmetrical key-board, each key of which controls a plurality of enharmonic pitches, electrical connections from said tone-producing elements to said key-board, each of said keys being adapted to control a plurality of different electrical circuits, one circuit for each pitch controlled by said key, and a selective control mechanism adapted to be manipulated to connect selectively and simultaneously different groups of tone-producing elements with said keyboard, the different tone-producing elements of each group being of different pitches, respectively, whereby the change of the selective control mechanism changes the pitches controlled by the keys of the key-board, substantially as described.
7. In a musical instrument, a key-board having keys arranged in groups, each group containing the same number of keys, and the keys within each group being symmetrically arranged, a plurality of tone-producing elements, operative connections from said keys to said tone-producing elements, said connections being such that each group of keys controls a corresponding group of tone-producing elements, the pitches of the respective tone-producing elements of each of said groups being separated by the same series of intervals.
8. In a musical instrument, in combination, a plurality of keys, said keys being arranged in horizontal rows and in banks from front to rear, the keys of each horizontal row being spaced apart the thickness of a key and the keys from front to rear being arranged one above the other at successive positions rearwardly at equal intervals and in direct alignment with each other, and a corresponding number of tone-producing elements, with controlling connections from said keys to said tone-producing elements.
9. In an instrument of the character referred to, a key-board comprising a plurality of vertical tiers of keys arranged side by side, each successive key, rearwardly, of a tier being directly over the one in front of it and all of the keys of a vertical tier lying between two parallel vertical planes coincident with their opposite sides, and the different tiers of keys being alternately positioned rearwardly and forwardly of each other for substantially the same length of a part of a key, whereby said key-board is symmetrical in arrangement in its horizontal rows and in its successive banks, and each key being spaced from its adjacent keys on both sides, as to the digital portion of the key, the thickness of a key therefrom, substantially as illustrated.
10. In a musical instrument, in combination, a plurality of tone-producing elements, a key-board for controlling said elements, said tone-producing elements being tuned to produce tones forming a series of perfect fifths divided into semitones of varying width such that the pitch ratios of the said tones forming and dividing each of said perfect fifths are to each other as the numbers 14, 15, 16, 17, 18, 19, 20, and 21, respectively, in the order named, from lowest to highest.
11. In a musical instrument, in combination, a plurality of tone-producing elements, a key-board for controlling said elements, said tone-producing elements being tuned to produce tones forming a series of perfect fifths divided into semitones of varying width such that the pitch ratios of the said tones forming and dividing each of said perfect fifths are to each other as the numbers 14, 15, 16, 17, 18, 19, 20, and 21, respectively, in the order named, from lowest to highest; together with transpositions of the said tones at intervals of a major third together with transpositions of all of said tones by octaves.
12. In a musical instrument, in combination, a plurality of tone-producing elements, a key-board for controlling said elements, said tone-producing elements being tuned to produce tones forming a series of perfect fifths divided into semitones whose respective relative pitch ratios are $\frac{15}{14}$, $\frac{16}{15}$, $\frac{17}{16}$, $\frac{18}{17}$, $\frac{19}{18}$, $\frac{20}{19}$, and $\frac{21}{20}$, in the order named from lowest to highest.
13. In a musical instrument, in combination, a plurality of tone-producing elements, a key-board for controlling said ele-

ments, said tone-producing elements being tuned to produce tones forming a series of perfect fifths divided into semitones whose respective relative pitch ratios are $\frac{1}{4}$, $\frac{1}{5}$, $\frac{1}{6}$, 5 $\frac{1}{7}$, $\frac{1}{8}$, $\frac{1}{9}$, and $\frac{1}{10}$, in the order named from lowest to highest, together with transpositions of the said tones by major thirds, together with transpositions of all of said tones by octaves.

10 14. In a musical instrument, in combination, a series of tone-producing elements, a key-board for controlling said elements, and operative connections from said key-board to the said tone-producing elements, the members 15 of said series of tone-producing elements forming tones at pitches determined by transpositions of groups of intervals, each group being composed of the same number of intervals, said groups varying from each 20 other by the substitution of enharmonic intervals, said keyboard being divided into groups of keys of the same number each as there are tones in each of said groups of intervals, said operative connections being such 25 that the keys in each of said groups of keys separately control the respective members of one of said groups of tone producing elements, and a selective control mechanism for simultaneously switching at will said key 30 groups from tone producing elements corresponding to the transpositions of one of said groups of intervals to tone producing elements corresponding to the transpositions of another of said groups of intervals, 35 the tone-producing elements simultaneously connected to said keyboard always being those whose tones form a transposition of the same group of intervals.

15 15. In a musical instrument, in combination with a plurality of tone-producing elements, a key-board the keys of which are operatively connected with said tone-producing elements, respectively, and a selective control mechanism adapted to set selectively for 20 use different groups of tone-producing elements in connection with said keys, the different groups of tone-producing elements producing tones which are transpositions at regular intervals of a plurality of series of tones, each of said series varying from each other through the substitution of enharmonic intervals, whereby said key-board can be selectively connected for group control with different groups of said tone-producing elements.

16 16. In a musical instrument, in combination, a plurality of tone-producing elements, a key-board the keys of which are adapted to be connected operatively with said tone-producing elements, and a selective control mechanism adapted, selectively, at will, as manipulated, to connect different groups of tone-producing elements with said key-board, the different groups of tone-producing elements forming tones which are transpositions

of groups of tones varying from each other by enharmonic intervals, substantially as described.

17. In a musical instrument, in combination, a series of tone producing elements, a key-board for controlling said elements, said key-board consisting of an unlimited number of keys per octave, the surface of each key presented to the player's finger (the digital surface) being of the same shape and size 70 as the corresponding surface of every other key, each of said surfaces being coincident with one of several parallel, equidistant planes, each key being positioned rearwardly proportionately to the height of the plane in which its digital surface lies, and said keys being so disposed that the said digital surfaces of alternate keys from left to right lie in the same plane, and operative 75 connections between said keys and said tone producing elements.

18. In a musical instrument, in combination, a series of tone producing elements, a key-board for controlling said elements, said keyboard consisting of an unlimited number 80 of keys per octave, arranged in banks, all keys having digital surfaces of the same shape and size, lying symmetrically disposed in substantially horizontal and equidistant planes, each key being positioned rearwardly 85 between parallel planes coincident with the opposite sides of said digital surfaces, proportionately to the height of the plane in which its digital surface lies, and said keys being so disposed that the digital surfaces of alternate keys from left to right lie in the same plane, and operative connections 90 between said keys and said tone producing elements.

19. In a musical instrument, in combination, a series of tone producing elements, a key-board for controlling said elements, said keyboard consisting of an unlimited number 95 of keys per octave, arranged in banks, all keys below the top bank having digital surfaces of the same shape and size, the digital surfaces of all keys lying symmetrically disposed in substantially horizontal and equidistant planes, each key being positioned rearwardly between parallel planes coincident with the opposite sides of said digital surfaces, proportionately to the height of the plane in which its digital surface lies, and said keys being so disposed that the digital surfaces of alternate keys from left to right 100 lie in the same plane, and operative connections between said keys and said tone producing elements.

20. In a musical instrument, in combination, a series of tone producing elements respectively tuned to produce the tones of the double diatonic series, a keyboard for controlling said elements, and operative connections between said keyboard and said tone producing elements.

tion, a series of tone producing elements respectively tuned to produce the tones of a plurality of transpositions of the chromatic series by octaves, a keyboard of the character described in claim 18 for controlling said elements, and operative connections between said keyboard and said tone producing elements such that contiguous keys of said keyboard control the speaking of tone producing elements forming consecutive tones of one of said transpositions of said chromatic series.

35. In a musical instrument, in combination, a series of tone producing elements respectively tuned to produce the tones of a plurality of transpositions of the chromatic series by octaves, a keyboard of the character described in claim 19 for controlling said tone producing elements such that contiguous keys of said keyboard control the speaking of tone producing elements forming consecutive tones of one of said transpositions of said chromatic series.

36. In a musical instrument, in combination, a series of tone producing elements respectively tuned to produce the tones of a plurality of transpositions of the double diatonic series by major thirds, and octaves of all tones of each of said transpositions, a keyboard for controlling said elements, and operative connections between said keyboard and those of said tone producing elements which form the tones of one of said transpositions and its octaves, with means of changing said operative connections to the respective tone producing elements which form the remainder of said transpositions and their respective octaves, one transposition at a time with its respective octaves.

40. 37. In a musical instrument, in combination, a series of tone producing elements respectively tuned to produce the tones of a plurality of transpositions of the chromatic series by major thirds, and octaves of all tones of each of said transpositions, a keyboard for controlling said elements, and operative connections between said keyboard and those of said tone producing elements which form the tones of one of said transpositions and its octaves, with means of changing said operative connections to the respective tone producing elements which form the remainder of said transpositions and their respective octaves, one transposition at a time, with its respective octaves.

38. In a musical instrument, in combination, a series of tone producing elements respectively tuned to produce the tones of the chromatic series and of the double diatonic series, and octaves of all tones of each of said series, a keyboard for controlling said elements, and operative connections between said keyboard and those of said elements which form the tones of one of said series and its octaves, with means of changing said

operative connections to the respective tone producing elements which form the other of said series and its octaves.

39. In a musical instrument, in combination, a series of tone producing elements respectively tuned to produce the tones of a plurality of transpositions of the double diatonic series and of a plurality of transpositions of the chromatic series and octaves of all tones of each of said transpositions, a keyboard for controlling said elements, and operative connections between said keyboard and those of said elements which form the tones of one of said transpositions and its octaves, with means of changing said operative connections to the respective tone producing elements which form the remainder of said transpositions, and their respective octaves, one transposition at a time, with its respective octaves.

40. In a musical instrument, in combination, a series of tone producing elements and electric control means therefor comprising in combination therewith a keyboard, each key of which control a plurality of electrical contacts, each of said contacts being connected to a tone producing device, a selective control mechanism having a plurality of contact members, each of which is provided with a plurality of contact elements, each of said contact elements being connected with a plurality of said key-controlled contacts, only one of the contacts controlled by any key being connected to the same contact element, a connecting member common to all of said contact members, said contact members as a group and said connecting member being relatively movable to connect selected contact elements simultaneously, one on each of said contact members, and a source of electrical energy to which is connected said connecting member and said tone producing devices.

41. In a musical instrument, in combination, a series of tone producing elements and electric control means therefor comprising in combination therewith a keyboard, each key of which controls an electrical contact and some keys of which control a plurality of electrical contacts, each of said contacts being connected with a tone producing device, a selective control mechanism having a plurality of contact members, each of which is provided with a contact element and some of which are provided with a plurality of contact elements, each of said contact elements being connected with a plurality of said key-controlled contacts, only one of the contacts controlled by any key being connected to the same contact element, a connecting member common to all of said contact members, said contact members as a group and said connecting member being relatively movable to connect selected contact elements simultaneously, one on each of said contact members, and a source of elec-

trical energy to which is connected said connecting member and said tone producing devices.

42. In a musical instrument, in combination, tone producing elements, a keyboard for controlling said elements, operative connections between said keyboard and said elements, and a selective control mechanism for changing said operative connections from one series of tone producing elements to another series of tone producing elements, said selective control mechanism having contacts to each of which is connected a separate series of tone producing devices sounding tones separated from each other by unisons, perfect fifths and octaves of said unisons and perfect fifths.

43. In a musical instrument, in combination, tone producing elements, a keyboard for
20 controlling said elements, operative connections between said keyboard and said elements, and a selective control mechanism for changing the said operative connections from one series of tone producing elements to another series of tone producing elements, said selective control mechanism having electrical contacts, each of which is connected to its own group of tone producing devices, each of said groups of tone producing devices consisting of those sounding tones separated from each other by unisons, perfect fifths, and octaves of said unisons and perfect fifths.

44. In a musical instrument, in combination, tone producing elements, a keyboard for controlling said elements, each key of said keyboard controlling a plurality of electrical contacts, a selective control mechanism consisting of a plurality of contact members, 35 each of said contact members being provided with a plurality of contact elements, said keys being divided into groups, the keys in each group having the same number of electrical contacts under their individual control, 40 each contact member of said selective control mechanism having the same number of contact elements as there are electrical contacts controlled by the individual keys of one of said key groups, all of the electrical contacts 45 of a given key group being respectively connected to the corresponding contact elements of one of said contact members of said selective control mechanism, and operative connections between said keys and said tone producing elements. 50 55

45. In a musical instrument, in combination, tone producing elements respectively tuned to produce the tones of an unlimited number of chromatic scales whose keynotes
60 are a perfect fifth apart, each of said chromatic scales consisting of the intervals, $\frac{1}{1}$, $\frac{1}{6}$, $\frac{2}{3}$, $\frac{1}{8}$, $\frac{4}{5}$, $\frac{4}{3}$, $\frac{1}{2}$, $\frac{3}{2}$, $\frac{1}{12}$, $\frac{5}{4}$, $\frac{7}{8}$, and $\frac{1}{16}$, a keyboard for controlling said elements, and
65 operative connections between said keyboard and said tone producing elements such that

the tone producing devices sounding consecutive tones of said chromatic scales shall be controlled by contiguous keys of said keyboard, all of said tone producing elements being simultaneously in operative connection 70 with the respective keys of said keyboard.

46. In a musical instrument, in combination, tone producing elements respectively tuned to produce the tones of an unlimited number of chromatic scales whose keynotes are a perfect fifth apart, each of said chromatic scales consisting of the intervals, $\frac{1}{2}$, $\frac{17}{12}$, $\frac{8}{7}$, $\frac{19}{12}$, $\frac{5}{4}$, $\frac{4}{3}$, $\frac{3}{2}$, $\frac{17}{12}$, $\frac{3}{2}$, $\frac{19}{12}$, $\frac{5}{4}$, $\frac{4}{3}$, $\frac{15}{8}$, and $\frac{2}{1}$, a keyboard 75 for controlling said elements and operative connections between said keyboard and said tone producing elements such that the tone producing devices sounding consecutive tones of said chromatic scales shall be controlled by contiguous keys of said keyboard. 80

47. In a musical instrument in combination, tone producing elements respectively tuned to produce the tones of an unlimited number of chromatic scales whose keynotes are a perfect fifth apart, each of said chromatic scales consisting of the intervals, $\frac{1}{2}$, $\frac{1}{3}$, $\frac{2}{3}$, $\frac{3}{5}$, $\frac{4}{5}$, $\frac{3}{2}$, $\frac{5}{3}$, $\frac{5}{4}$, $\frac{16}{9}$, $\frac{15}{8}$, and $\frac{1}{1}$, a keyboard for controlling said elements and operative connections between said keyboard and said tone producing elements such that the tone producing devices sounding consecutive tones of said chromatic scales shall be controlled by contiguous keys of said keyboard all of said tone producing elements being simultaneously in operative connection with the respective keys of said keyboard. 100

48. In a musical instrument, in combination, tone producing elements respectively tuned to produce the tones of an unlimited number of chromatic scales whose keynotes are a perfect fifth apart, each of said chromatic scales consisting of the intervals, $\frac{1}{2}$, $\frac{1}{3}$, $\frac{2}{3}$, $\frac{3}{5}$, $\frac{4}{5}$, $\frac{5}{8}$, $\frac{3}{4}$, $\frac{5}{6}$, $\frac{2}{5}$, $\frac{8}{5}$, $\frac{5}{3}$, $\frac{16}{9}$, $\frac{15}{8}$, and $\frac{2}{1}$, a keyboard 105 for controlling said elements, and operative connections between said keyboard and said tone producing elements such that the tone producing elements sounding consecutive tones of said chromatic scales shall be controlled by contiguous keys of said keyboard. 110

49. In a musical instrument in combination, tone producing elements respectively tuned to produce the tones of an unlimited number of chromatic scales whose keynotes are a perfect fifth apart, each of said chromatic scales consisting of the intervals, $\frac{1}{2}$, $\frac{1}{3}$, $\frac{2}{3}$, $\frac{3}{5}$, $\frac{4}{5}$, $\frac{3}{4}$, $\frac{2}{5}$, $\frac{5}{3}$, $\frac{3}{2}$, $\frac{5}{4}$, $\frac{6}{5}$, and $\frac{2}{1}$, a keyboard for controlling said elements and operative connections between said keyboard and said tone producing elements such that the tone producing elements sounding consecutive tones of said chromatic scales shall be controlled by contiguous keys of said keyboard all of said tone producing elements being simultaneously in operative connection with the respective keys of said keyboard. 120 125

50. In a musical instrument, in combination: 130

tion, tone producing elements respectively tuned to produce the tones of an unlimited number of chromatic scales whose keynotes are a perfect fifth apart, each of said chromatic scales consisting of the intervals, $\frac{1}{4}, \frac{1}{5}, \frac{2}{3}, \frac{4}{5}, \frac{3}{4}, \frac{6}{5}, \frac{5}{4}, \frac{9}{8}, \frac{10}{9}, \frac{15}{14}$, and $\frac{2}{1}$, a keyboard for controlling said elements and operative connections between said keyboard and said tone producing elements such that the tone producing elements sounding consecutive tones of said chromatic scales shall be controlled by contiguous keys of said keyboard.

51. In a musical instrument, in combination, tone producing elements, respectively 15 tuned to produce the tones of an unlimited number of similar chromatic scales whose keynotes are a perfect fifth apart, a keyboard for controlling said elements and operative connections between said keyboard and said 20 tone producing elements such that the tone producing elements sounding consecutive tones of said chromatic scales shall be controlled by contiguous keys of said keyboard, all of said tone producing elements being 25 simultaneously in operative connection with the respective keys of said keyboard, said

chromatic scales being tuned to any system except equal temperament.

52. In a musical instrument, in combination, tone producing elements respectively 30 tuned to form the tones of a plurality of transpositions of groups of tones, each group consisting of an unlimited number of similar chromatic scales whose keynotes are a perfect fifth apart, said scales being tuned 35 in any system except equal temperament, a keyboard for controlling said elements, operative connections between said keyboard and said elements such that the keys of said keyboard shall be in simultaneous connection 40 with the tone producing elements forming the tones of one of said groups, and a selective control mechanism for changing said operative connections so that said keys shall, after the use of said mechanism, be respectively connected to the remaining of said groups of tone producing devices, one at a time, selectively.

Signed at Los Angeles, Los Angeles County, California, this 12th day of April, 1923.

FREDERICK W. FELLOWS.

CERTIFICATE OF CORRECTION.

Patent No. 1,685,401.

Granted September 25, 1928, to

FREDERICK W. FELLOWS.

It is hereby certified that error appears in the printed specification of the above numbered patent requiring correction as follows: Page 6, under heading equivalent vibration ratios, lines 5 to 16, the first eight fractions should have the denominator "ten and two-thirds" instead of having a denominator of "ten", with "two-thirds" printed as a separate fraction. The numerator of each of these fractions is correct; same page, same heading, lines 100 to 109, the denominator of the first two fractions, should read "seven and one-ninth" instead of "seven" with separate fractions, and the next four fractions, the denominator should read "ten and two-thirds" instead of "ten" with separate fractions; and that the said Letters Patent should be read with these corrections therein that the same may conform to the record of the case in the Patent Office.

Signed and sealed this 5th day of February, A. D. 1929.

(Seal)

M. J. Moore,
Acting Commissioner of Patents.
